UNITED STATES PATENT OFFICE.

ELDRIDGE A. MCKEEVER, OF CATASAUQUA, PENNSYLVANIA.

AUXILIARY AIR-INLET DEVICE.

Application filed November 13, 1924. Serial No. 749,758.

To all whom it may concern:

Be it known that ELDREDGE A. MCKEEVER, a citizen of the United States, residing at Catasauqua, in the county of Lehigh and 5 State of Pennsylvania, has invented certain new and useful Improvements in Auxiliary Air-Inlet Devices, of which the following is a specification.

This invention relates to new and useful improvements in attachments for carburetors, and more particularly to an air gasket therefor, the primary object being to provide a device of this character which will, when effectively applied, increase the 10 power of the motor, increase the mileage and eliminate carbon to a considerable extent.

A further object resides in providing a device of this character interposed between the carburetor and the intake manifold 20 which will purify and thoroughly vaporize the gasoline, under which conditions it is a well known fact that a motor will run perfectly and avoid overheating.

Still another object of the invention resides in providing an air intake pipe in connection with a gasket which is provided with a slot arranged in such a manner that substantially an air curtain is caused to extend across the opening of the gasket, when 30 the motor is in operation, so that the gasoline will be thoroughly mixed with the air and vaporized as it is drawn into the manifold.

Still another object of the invention resides in providing a device of this character which is simple and durable in construction, inexpensive to manufacture, and one which may be considered as effective and useful in operation.

With these and other objects in view my invention consists in the novel features of construction, combination and arrangement of parts as will be hereinafter referred to and more particularly pointed out in the 45 specification and claims.

In the accompanying drawing forming a part of this application,

Figure 1 is a side elevation of an intake manifold and carburetor showing my improved attachment applied to use thereon;

Figure 2 is an elevation of the gasket removed with the air intake pipe attached thereto;

Figure 3 is a horizontal section as seen 55 on the line 3-3 of Fig. 2; and

Figure 4 is a vertical section as seen on the line 4-4 of Fig. 2.

In describing the invention I shall refer to the drawing in which similar reference characters designate corresponding parts throughout the several views, and in which 60 1 designates the intake manifold of a hydrocarbon motor and 2 the carburetor therefor, the latter being of any preferred type or construction.

My improved attachment comprises a gasket of elongated type numbered in the drawing as 3 which is secured in place between the carburetor and the intake manifold by means of bolts which extend through 65 two bolt holes 4 formed adjacent the ends of the gasket. The central opening 5 in the gasket registers with the exit opening of the carburetor and similar opening of the manifold so that the air and gasoline readily pass therethrough to the motor and this opening is tapered, that is, the edges of the opening are beveled so as to draw the gasoline in direct contact with the current of air, as will appear more fully from the description herebelow.

Extending longitudinally through the lower portion of the gasket is an air tube 6 formed preferably of copper and intersecting the opening 5 toward the wider end 75 thereof. This tube terminates at its inner end within the gasket, as clearly shown in dotted lines of Fig. 2 of the drawing and the portion extending beyond the gasket is 80 bent in U-shaped formation as shown at 7, the extreme free end of this U-shaped portion being open. The air is drawn through this open end of the tube and this U-shaped portion is provided to prevent the escape of gasoline after the motor has stopped, it being obvious that any gasoline which may run back from the intake manifold after the motor has been stopped will drain into the U-shaped portion of the copper tubing. When the motor is again started, this 85 excess gasoline will act as a priming charge, assuring instant starting of the motor.

As stated above, the tube 6 intersects the wider portion of the opening 5, as clearly shown in Figs. 2 and 4 of the drawing and the upper portion of the tube at this point is provided with a restricted slot or elongated opening 8 which faces upwardly toward the opening 5 and is of a width equal to the diameter of said opening at the smaller end 100 105 110

thereof, as more clearly shown in Fig. 3 of the drawing. This slot of the width mentioned permits the air to be drawn upwardly when the motor is in operation and thus substantially a curtain of air of a width equal to the innermost diameter of the opening 5 is provided. This air curtain obviously intersects the flow of gasoline from the carburetor to the manifold, thoroughly mixing with 10 said gasoline, purifying the latter and thoroughly vaporizing it. Obviously, when the gasoline is thoroughly vaporized the motor will develop greater power, more speed and carbon will be eliminated or appreciably reduced.

15 The periphery of the opening 5 at the lower portion thereof is provided with a restricted slot member 9 in the drawing which leads toward the opening 8 in the tube 6, so that when the motor is stopped any gasoline remaining in the manifold will drain readily into the copper tube 6 and further into the U-shaped portion 7 of said tube.

20 I am aware that others have attempted to 25 accomplish what I claim to accomplish by my invention, but I am not aware that the results have been accomplished through the specific construction hereabove described and illustrated in the drawing. I am further not 30 aware that anyone has been able to accomplish the desired results in a manner as efficient as that set forth above.

35 From the foregoing description of the construction of my improved device, the operation thereof will be readily understood and it will be seen that I have provided a 40 simple, inexpensive and efficient means for carrying out the objects of the invention.

45 While I have particularly described the 40 elements best adapted to perform the functions set forth, it is obvious that various changes in form, proportion, and in the minor details of construction may be resorted to without departing from the spirit or sacrificing any of the principles of the invention.

Having thus described my invention, what I claim is:—

50 1. An auxiliary air mixing device comprising a gasket adapted to be interposed between a carbureter and intake manifold of an engine, and having a central tapered opening therein, an air pipe longitudinally extending through the thickness of said gasket and transversely intersecting the opening of the latter, said pipe being provided with a slot in the portion intersecting the opening, whereby to permit substantially a 55 curtain of air to be drawn across the inner

end of said opening, as and for the purposes 60 described.

2. An auxiliary air mixing device comprising a gasket adapted to be interposed between the carbureter and intake manifold of an engine, said gasket being provided with a central opening tapering toward one end thereof, the wall of said opening toward the lower edge of the gasket being provided with a transverse groove, an air pipe projecting longitudinally through the thickness 70 of the gasket and extending across the lower portion of said opening, said pipe having a slot formed therein facing upwardly, whereby to permit an uninterrupted curtain of air to be drawn across the opening in said gasket, the groove in the wall of said opening leading toward the slot in said pipe to permit draining of gasoline from the manifold when the engine is stopped.

3. An auxiliary air mixing device comprising a gasket adapted to be interposed between the carbureter and intake manifold of an engine and provided with a tapering bore, an air pipe disposed longitudinally through the thickness of said gasket and 80 projecting across the bore in said gasket at the lower portion thereof, the inner end of said pipe terminating within the body of the gasket and the outer end thereof being formed into an integral enlarged U-shaped 85 member to receive gasoline drained from the manifold at predetermined times, said pipe being provided with a restricted slot at its intersection with the aforesaid bore and of a length equal to the diameter of the reduced 90 end of said bore, as and for the purposes described.

4. An auxiliary air mixing device comprising a gasket provided with a tapering bore, the wall of said bore nearest the lower 100 edge of said gasket being provided with a transverse groove, an air pipe projected longitudinally through the gasket and intersecting the aforesaid bore at the lower portion thereof, said intersecting portion of the 105 pipe being provided with a slot of restricted width facing upwardly and of a length equal to the diameter of the reduced end of said bore, to permit a curtain of air to be drawn across said bore, the inner end of said pipe terminating in the body of the gasket and the outer end thereof being formed into an integral enlarged U-shaped member 110 to one side of said gasket and in the same vertical plane with the latter, as and for the 115 purposes described.

In testimony whereof I affix my signature.

ELDRIDGE A. McKEEVER.
